UNITED STATES PATENT OFFICE

2,254,859

INDICATOR FOR THE COOLING LIQUID OF
INTERNAL COMBUSTION ENGINES

Elmer J. Richley, Cleveland, Ohio

Application May 21, 1938, Serial No. 209,254

2 Claims. (Cl. 73—51)

This invention relates to means for measuring a property of the cooling liquid for internal combustion engines and particularly to those auxiliary devices accompanying or supplementing capillarimeters such as described in the Patent No. 2,059,961 granted to me November 3, 1936.

As conducive to a clearer understanding of this invention, it may be well to point out that the gauge described in detail in the aforementioned patent works and operates satisfactorily in automobiles of somewhat older design and construction, and particularly in those vehicles in which the normal level of the radiator liquid is lower than the capillary gauge mounted on the dash-board. In the more modern automobiles those designed with high radiators and comparatively low dash-boards; because of the fact that water has the tendency to seek its own level, the capillarimeters could not at all times be used properly and accurately. The liquid in such instances flooded the gauge and could not drain off sufficiently to clear the chambers, cavities and channels so as to leave the proper amount of the liquid to be tested in the reservoir in which the capillary testing tube was inserted. This difficulty was often aggravated when the automobile happened to be headed on an incline.

It is, therefore, the principal object of the invention to provide an apparatus which facilitates the gauging of the condition and the freezing characteristics of the liquid used for cooling automobile engines.

Other objects and a fuller understanding of this invention may be had by referring to the following specification, taken in conjunction with the accompanying drawing and in which like parts are referred to by like characters and in which:

Figure 1 is a side view of an automobile engine having a trap-valve attached thereto and showing the circulation of radiator liquid through the engine and test circuit;

Figure 2 is a schematic view of the test circuit showing capillarimeter in readable condition;

Figure 3 is a side sectional view of the trap-valve, taken along the line 3—3 of Figure 5;

Figure 4 is a front sectional view of the trap-valve, taken along the line 4—4 of Figure 5;

Figure 5, is a part plan and part sectional view of the trap-valve, taken along the line 5—5 of Figure 3;

Figure 6 is a horizontal sectional view of the device, taken along the line 6—6 of Figure 3;

Figure 7 is an enlarged sectional view of the valve mechanism; and

Figure 8 is a horizontal sectional view of the valve mechanism, taken along the line 8—8 of the Figures 4 or 7.

In the drawing Figure 1 is a rather comprehensive view of the capillarimeter and the trap-valve constituting this invention and connected to an automobile engine. In this figure, there is shown the cooling liquid 19 circulating through the radiator 31, the water-jacket of the engine 33, the pump 34 and the connecting hose 32 and 35; and also passing through the test circuit consisting of the capillarimeter 10, which is mounted on the dash-board 16, the trap-valve 20, the filter 27, and the connecting pipes 14, 15, and 15a connected in parallel thereto.

Briefly described the capillarimeter 10, consists of a chamber 12, in which there is a longitudinal cavity 17, an adjacent channel 18 and a by-pass 21, which by-pass causes a reservoir 22 to be formed in the bottom of the cavity 17, in which a calibrated capillary tube 11 is inserted for the purpose of gauging the character of the liquid. The channel 18 is provided with an overflow valve 23 and an air vent 24. The chamber 25 openings are suitably tapped or provided with means for the attachment thereto of the feed pipe 15a and the drain pipe 14.

The trap-valve 20 is connected by the pipe 15 to the pressure side of the water pump 34 with the filter 27 interposed between it and the pump 34 to keep the test circuit free from foreign matter or solids which might disrupt its operation, interfere with its efficiency or which might clog the capillary tube 11. It is also connected by the inclined pipe 15a to the capillarimeter 10. The capillarimeter 10 which may be positioned lower than the top level of the liquid 19 in the radiator 31, is connected to the said radiator by the pipe 14. The pipe 14, however, must at some portion of its length, such as the point 37 thereon, be higher than the radiator over-flow pipe 36 so as to prevent too much of the liquid 19 from flowing back into the capillarimeter 10 when the motor stops running, or at least not more of it than the trap-valve 20 can accommodate. The outlet pipe 14 must also be somewhat higher than the level of the radiator liquid 19 and above the top of the overflow pipe 36 to prevent a syphonal action from the capillarimeter 10.

The trap-valve 20 itself is made of two concave plates or cups 41 and 42 respectively, their concave sides facing each other and their brims or edges 43 firmly fastened together with small bolts 44 and nuts 45. The two cups 41 and 42 thus assembled, form a hollow chamber.

Interposed between the two cups 41 and 42 is a floating diaphragm 46 made of a sheet of flexible or pliable material which is impervious to water. A disk of rubber or similar elastic material may also be used satisfactorily to simply divide the hollow chamber into lower and upper variable sized compartments 47 and 48 respectively.

To the diaphragm 46 is attached a simple valve 7 which is composed of a valve-case 49, a valve-seat 51, a valve-head 52 and a compression spring 53. The valve-case 49 is internally threaded so as to receive the externally threaded valve-seat 51, and also has several apertures 54 for allowing the liquid 19 to pass through. The valve-seat 51 has a face 55 and is provided with an internal shoulder 57 and an external flange 56. The valve-head 52 snugly fits the face 55 and closes off the apertures 54 when the compression spring 53 is in its normal position and which position is shown in the Figure 7. Attached to the bottom of the valve 7 or particularly to the valve-seat 51, is a simple metal loop 68. The valve-head 52 is connected to the plunger-head 58 by the piston rod 59, and is kept in its normal position by the compression spring 53 which rests at one end on the shoulder 57 and which presses against the plunger-head 58 at its opposite end. To facilitate fastening the valve 7 to the aforementioned diaphragm 46 and to keep it in an upright position, the diaphragm 46 is sandwiched in between two rigid rings or disks of metal, fiber or other suitable material which are indicated in the drawings by the characters 61 and 62 respectively. The lower disk 61 and the upper disk 62 are perforated to accommodate the valve-seat 51 and are firmly held together by the flange 56 and the valve-case 49 which is threadedly attached thereto.

The cups 41 and 42 are formed with top and bottom shelves 64 and 63 respectively to accommodate the disks 61 and 62. The inclined sides 65 and 66 of the cups 41 and 42 cause the valve 7, by reason of the disks 61 and 62 fitting the shelves 63 and 64, to be in a vertical position and also for it to be centered and over the inlet tube 67 which is attached to the bottom of the cup 41.

The inlet tube 67 is simply a piece of pipe in which there is suspended by the pin 69 an expansion spring 71, one end of which is attached to the loop 68 on the valve 7. The spring 71 has a natural tendency to keep the valve 7 down, causing the pliable material 46 and the disks 61 and 62 to shrink or decrease the size of the lower compartment 47, and to correspondingly increase the capacity of the upper compartment 48. However, when the liquid 19 is forced through the inlet tube 67 under pressure, it causes the valve 7 and the attached disks 61 and 62 and the diaphragm 46 to rise, thereby shrinking or decreasing the capacity of the upper compartment 48 and correspondingly increasing the size of the lower compartment 47. When this happens, the plunger-head 58 strikes the top portion of the cup 42 and opens the valve 7 as clearly shown in Figure 3.

In operation, the liquid 19 circulates through the test circuit as follows: Starting at the pump 34 it passes through the pipe 15, is cleansed by the filter 27, and passes into and through the valve-trap 20 constituting a feature of this invention. The liquid 19 having entered and filled the lower compartment 47 through the inlet tube 67, forces the diaphragmal pliable material 46

with its attached valve 7 upward until the plunger-head 58 strikes the top 42 and thereby separates the valve-head 52 from the valve-seat 51. This opening permits the liquid 19 to enter into the upper compartment 48 through the apertures 54, and from there to the capillarimeter 10 by way of the outlet coupling 75 and the pipe 15a. From the capillarimeter 10, the liquid goes back to the place of beginning by way of the pipe 14. The construction and scheme of circulation of the liquid 19 through the capillarimeter 10, is specifically described in detail in the Patent No. 2,059,961 heretofore referred to.

The outlet coupling 75 is slightly off the center 15 of the top portion 74 of the cup 42 so as not to interfere with the operation of the valve 7 which is in and moves in a central vertical line.

The motor may be stopped to take a reading of the capillarimeter 10. When this is done, the 20 pressure ceases and the expansion spring 71 contracts and draws the valve 7 downward, to permit its closure by spring 53. Simultaneously the space in the upper compartment 48 is increased and the liquid in the pipe 14 from the point 37 to 25 the capillarimeter 10, the surplus liquid in the capillarimeter itself, and all or part of the liquid in the pipe 15a flows back into the trap-valve 20, thereby enabling the capillary tube 11 to function properly. This is quite clearly illustrated in the 30 schematic view Figure 2. If the motor is not stopped but is throttled down to a point where the water pressure is not great enough to overcome the tension of the spring 71, a reading may be also taken.

The quantity of liquid that is required to remain in the reservoir 22 of the capillarimeter 10 for the capillary tube 11 to function, is very small. About one cubic centimeter is sufficient. Therefore, the pipes 14, 15 and 15a need not be very 40 large and by using comparatively small diameter tubing for this purpose, the upper compartment 48 likewise need not be very large to accommodate the liquid drained and trapped therein. As a result, the herein described trap-valve may be 45 made small, compact, inexpensive and installed so as not to interfere or obstruct any other devices on the automobile.

While the invention is described herein in its preferred form and while certain specific terms 50 and language have been used, it is to be understood that the present disclosure is illustrative rather than restrictive, and that no limitations upon the invention are intended other than those which are imposed thereon by the scope of the 55 appended claims.

I claim:

1. In an apparatus for determining an attribute of the liquid contained in the cooling system of an internal combustion engine wherein the liquid 60 is circulated through the water jacket and radiator associated with said engine by means of a circulating pump, a capillarimeter for gauging the liquid, said capillarimeter having a reservoir for trapping a predetermined quantity of said liquid, a conduit from the top of said capillarimeter to said system, a trap situated below said capillarimeter and connected thereto and to the circulating pump of said engine by conduits, valve means in the trap and so constructed 65 and arranged to permit normal circulation of a part of said liquid therethrough when said engine is operated at driving speed and to prevent circulation when said engine is stopped or idling, means forming an expansible chamber in said trap and actuated upon closure of said valve, the 70 75

combined capacity of said chamber and the conduit connecting the capillarimeter and said trap being of such size as to receive and contain the excess of liquid in said apparatus when said valve is closed.

2. In an apparatus for determining an attribute of the liquid contained in the cooling system of an internal combustion engine wherein the liquid is circulated through the water jacket and radiator associated with said engine by means of a circulating pump, a capillarimeter for gauging the liquid, said capillarimeter having a reservoir for trapping a predetermined quantity of said liquid, a conduit from the said capillarimeter to said system, a trap connected to the capillari-

5 meter and to the circulating pump of said engine by conduits, valve means in the trap and so constructed and arranged to permit normal circulation of a part of said liquid therethrough when said engine is operated at driving speed and to prevent circulation when said engine is stopped or idling, means forming an expansible chamber in said trap and actuated upon closure of said valve, the combined capacity of said 10 chamber and the conduit connecting the capillarimeter and said trap being of such size as to receive and contain the excess of liquid in said apparatus when said valve is closed.

ELMER J. RICHLEY.
